UNITED STATES PATENT OFFICE.

HANS FREDERICK HOFER, OF KOFU, JAPAN.

METHOD OF AND MEANS FOR IDENTIFYING SKEINS OF FIBER SUCH AS SILK.

Application filed December 20, 1924, Serial No. 757,235, and in Japan May 31, 1924.

This invention relates to identification means for skeins made from threads of any material but more particularly for skeins of silk.

5 Raw silk is exported and forwarded to the manufacturers in the form of skeins and in order to be able to trace the origin of imperfections contained in the silk so that such defects may be remedied if possible, 10 it has been found desirable that each skein of silk should be supplied with some kind of identification means indicating the operator who has made the skein.

Japanese raw silk skeins are not supplied 15 with any such identification means but skeins from some of the Italian raw silk factories are often provided with some means or other whereby the operator who has wound the silk thereof may be identified. 20 Usually such means comprises a slip of paper on which is printed the name or the number of the operator who has made the skein and which is loosely inserted in the skein. Owing to the fact that such 25 means is loosely placed in the skein it is liable to get lost when the skein is being unwound. Also, owing to the fact that such means is made of paper it will become crumpled up if the skein is dampened for 30 unwinding as is often the case, and will have a tendency to become entangled with the threads thereby causing breakages. Further, if no such breakages occur and the 35 paper is not lost, the writing thereon will have become practically illegible due to the crumpling and damping.

One of the objects of the present invention is to provide an identification means for such skeins which cannot possibly become 40 lost during the unwinding of the skein.

A further object of the invention is to provide an identification means which will have no tendency to become entangled with the threads of the skein.

45 A further object of the invention is to provide an identification means which will have no tendency to become illegible either during the transport of the skein or due to operations associated with the unwinding.

50 In order that the invention may be clearly understood reference is made to the accompanying drawing in which:—

Fig. 1 is a perspective view of the means

used for winding skeins having a complete skein wound thereon and indicating the 55 commencement of the winding of a second skein.

Fig. 2 is a diagrammatic view of the identification means; and

Fig. 3 is a table indicating a preferred 60 code for use in marking the identification means.

According to the present invention, the identification means comprises a cotton or other thread preferably heavier than the 65 silk thread, which is adapted to be attached to the initial end of the skein, that is, to the end of the silk thread from which the winding of the skein is commenced. The cotton or the like thread is provided with 70 a plurality of series of markings each series being a code indication of the operator who has made the skein. Preferably the cotton or the like thread is about half a yard long and the series of markings are of such a 75 character that a comparatively large number of such series of markings is contained upon the single length of thread, whereby if the thread is broken the remaining length will contain complete identification means. 80

The code markings preferably comprise dots and dashes somewhat of the style of the Morse code, such dots and dashes being combined in different ways to indicate the numerals 1-9 and 0 as indicated in Figure 3 85 of the drawings. Each operator is known or identified in the factory by a number and each series of markings on the identification thread will consist of a plurality of dots and dashes arranged according to the code 90 to indicate the operator's number. Suppose for instance that the operator's number is 758 then the marking used for indicating this number will be

— — . . .

7 5 8

To distinguish clearly between the code markings of each figure of the number the intervals between the code markings of each figure is less than the intervals between the code markings of different figures. Also the intervals between the different series of code markings is preferably considerably greater than the intervals between the code markings of the different figures of each number. 105 Thus the different series of markings on

each identification thread will be clearly separated from each other and the code markings will be easy to decipher.

A suitable spacing to be adopted is as follows:—

5 Intervals between series of markings or numbers 1".

Intervals between the markings corresponding to the figures in each series 1/3".

10 Intervals between markings which make up the separate figures 1/9".

The code markings are applied to the threads by any suitable means as by printing.

15 The identification thread is attached to the initial end of the silk thread before it is wound into the skein as is clearly shown in Fig. 1 of the drawings. Referring to this figure *a* represents the usual skeleton winding device upon which the skeins are wound. A fully wound skein is indicated at *b*. A second skein is to be wound on the device in the position indicated at *c* and the initial end *d* of the silk thread to be wound on to the device is provided with an identification thread *e* fixed thereto in any suitable manner as by tying. During winding of the skein the identification thread will be treated as part of the skein and thus when the skein is fully wound such thread will be located within the skein in a fully extended condition. There will therefore be no crumpling of the identification means and thus it will not become entangled with the silk threads of the skein and the markings thereon will not have a tendency to become obliterated. Also there will be no possibility of the identification means becoming lost and thus if the operator during the unwinding of the skein notices any imperfections therein, the identification means will be clearly exposed to view when the winding is finished, and such means may be forwarded to the makers of the skein to help them in discovering the cause of the defect.

45 What I claim is:—

1. A skein of fiber such as silk having identification means thereon, such means comprising a distinguishing thread, attached to the initial end of the fiber and being adapted to be wound with the skein so that said thread will be attached to the terminal end of the skein when unwound.

50 2. A skein of fiber such as silk having identification means thereon, such means comprising a thread having identification markings thereon, attached to the initial end of the fiber and being adapted to be wound

with the skein so that said thread will be attached to the terminal end of the skein when 60 unwound.

55 3. A skein of fiber such as silk having identification means thereon, such means comprising a distinguishing thread attached to the initial end of the fiber, and being adapted to be wound with the skein so that said thread will be attached to the terminal end of the skein when unwound, such thread having a series of dots and dashes thereon, such dots and dashes being arranged according to a code to indicate the operator who has made the skein.

60 4. A skein of fiber such as silk having identification means thereon, such means comprising a distinguishing thread attached to the initial end of the fiber, and being adapted to be wound with the skein so that said thread will be attached to the terminal end of the skein when unwound, such thread having a plurality of series of dots and dashes thereon, each of such series of dots and dashes being arranged according to a code to indicate a number, the series of dots and dashes representing the numbers being arranged a greater distance apart than the dots and dashes of such series which represent the separate figures of the number.

65 5. A skein of fiber such as silk having identification means thereon, such means comprising a distinguishing thread attached to the initial end of the fiber, and being adapted to be wound with the skein so that said thread will be attached to the terminal end of the skein when unwound, such thread having a plurality of series of dots and dashes thereon, each of such series of dots and dashes being arranged according to a code to indicate a number, the series of dots and dashes representing the numbers being arranged a greater distance apart than the dots and dashes of such series which represent the separate figures of the number, and the dots and dashes representing the individual figures of the number being arranged a less distance apart than the dots and dashes representing the different figures.

70 6. A method of identifying skeins of fiber such as silk, which consists in attaching to the initial end of such fiber a thread containing identification markings and winding such thread with the fiber when making the skein whereby, when the skein is unwound, such distinguishing thread will be on the terminal end thereof.

In testimony whereof I affix my signature
HANS FREDERICK HOFER.
